PRODUCTION OF ARTIFICIAL MATERIALS

William Ivan Taylor and Alfred Herbert Woodruff, Spondon, near Derby, England, assignors to Celanese Corporation of America, a corporation of Delaware

Application December 27, 1933, Serial No. 704,117
In Great Britain January 6, 1933

11 Claims. (Cl. 18—8)

This invention relates to the production of artificial materials and is particularly concerned with the production of artificial filaments by the dry or evaporative method.

U. S. application S. No. 375,150 filed 1st July, 1929 describes a process for the manufacture of artificial filaments by the dry or evaporative method in which a spinning solution is extruded in the form of filaments into a vacuum or into an evaporative medium at substantially reduced or sub-atmospheric pressure. The specification referred to describes a spinning apparatus resembling in general form a well-known type of apparatus in which a series of rectangular compartments containing spinning jets is provided with doors giving access to such jets, and is heated by banks of heating pipes proceeding from one end of the series of compartments through the intervening partitions to the other end. In this manner, the heating of all the compartments may be readily controlled, and uniformity between them is obtained. The pressure difference between the inside of each compartment and the outside atmosphere may, however, amount to 5 inches of mercury and upwards as compared with the difference of but a few inches of water which may be employed in ordinary dry-spinning processes. In consequence, difficulties arise in rendering the compartments gas-tight, not only because the heating pipes pass through the walls of the compartments, but also because provision must be made to render the spinning jets accessible for the attention which they require, e. g. during the starting of the spinning operation.

These difficulties may be overcome or greatly reduced by the present invention. For this purpose, the spinning apparatus may comprise a chamber of large cross-section containing a spinning jet, and a tubular cell of small cross-section leading from said chamber for the reception of the filaments extruded from such jet, together with means for creating and maintaining a vacuum within said cell and around said jet, and means for making a gas-tight closure around the jet and the end of the cell. The small diameter of the cell reduces the volume to be evacuated, and greatly facilitates the creation and maintenance of vacuum.

With this arrangement, heating of the cell may be effected externally, and a convenient arrangement comprises the use of a rectangular casing surrounding the tubular cell, and, it may be, forming a continuation of the chamber containing the spinning jet, and constituting therewith

an outer chamber enclosing both the spinning jet and the tubular cell. Heating pipes may be contained within such a casing, or a series of such casings, without entering the tubular cell or cells, thus overcoming the difficulty of making gas-tight joints at points of entry of such heating means.

Furthermore, provision may readily be made in the large chamber containing the spinning jet for rendering the jet accessible, and for making a gas-tight closure around it and the end of the tubular cell. If the tubular cell makes a gas-tight joint with the chamber, a door or trap in the chamber containing the jet may suffice, suitable gaskets or packing being provided to make the door gas-tight. Alternatively, a hood-like member may be provided inside the chamber, making a gas-tight joint around the jet, bedding down on the end of the tubular cell, and adapted to slide away from the tubular cell to give access to the jet. The hood closing the top of the tubular cell may conveniently be arranged to fit around the filter candle through which the spinning solution passes on its way to the joint of extrusion, or on to a suitable attachment secured to the candle. Thus, for example, the hood may be a sliding fit about the candle and may be heavy in weight so that its own weight presses it down upon a rubber ring around the upper edge of the cell to make a gas-tight joint, the action of the vacuum within the cell also assisting considerably in sealing the joint.

Means are preferably provided, e. g. in connection with the hood at the top of the cell, for connecting the interior of the cell with the outside atmosphere and so relieving the vacuum before the hood is raised to render the spinning jet accessible.

The spinning cell according to the present invention may be provided with any or all of the auxiliary apparatus described in the said U. S. application S. No. 375,150 and U. S. application S. No. 484,788 filed 27th September, 1930. Thus for example, the vacuum in the cell may be maintained by drawing off the contents of the cell to a solvent recovery plant which itself by the condensation of the recovered solvent assists in maintaining the vacuum. Separate means may be provided for effecting initial exhaustion of the cell, and further means may also be provided for introducing any desired quantity of evaporative medium, e. g. warm air or the like. In addition heating means may be provided for bringing the spinning solution to any desired temperature prior

to its extrusion from the spinning jet. Suitable means for this purpose are described in U. S. application S. No. 375,151 filed 1st July, 1929.

While the invention is applicable generally to the production of filaments by the dry or evaporative method, it is particularly convenient in connection with the production of filaments of cellulose acetate or other organic derivatives of cellulose. Examples of other organic derivatives of cellulose are other esters of cellulose, such as cellulose formate, cellulose propionate and cellulose butyrate, and the cellulose ethers such as ethyl and benzyl cellulose. Such organic derivatives of cellulose may be dissolved in any suitable solvents, e. g. acetone, with or without high boiling solvents or plasticizers. It is an advantage of the present invention, however, that it enables solvents of relatively low volatility to be employed, these being generally more easily recoverable from the gases drawn out of the cell. Furthermore, by the employment of a vacuum or substantially reduced sub-atmospheric pressure in the spinning cell, filaments of good round or bulbous cross-section are formed, and the nature of the cross-section persists along the length of the filaments, giving great uniformity.

While, in the present description, the filaments have been assumed to take a generally downward and vertical direction during spinning, it is to be understood that the invention is not limited to such form of spinning operation.

By way of example two forms of apparatus according to the invention will now be described in greater detail with reference to the accompanying drawings in which:—

Figure 1 is a sectional side elevation of a spinning apparatus according to the invention,

Figure 2 is a part sectional view of a detail of Figure 1,

Figure 3 is a sectional side elevation, and Figure 4 a sectional front elevation of a further form of spinning apparatus according to the invention.

In the drawings, the spinning apparatus comprises a chamber 3 fitted with a supply pipe 4, filter candle 5 and spinning jet 6. Filaments 7 extruded from the jet 6 pass down a narrow tubular cell 8 inside a casing 19 forming an extension of the chamber 3 and constituting therewith an outer chamber enclosing both jet 6 and cell 8. The filaments leave the cell 8 by a branch tube 9, being deflected by a thread guide 10 into the branch tube. The tubular cell 8 may be of any convenient cross-section, e. g. round, square or rectangular. The end of the branch tube 9 is fitted with a closure 11 of the kind described in U. S. application S. No. 484,788 and with a vacuum gauge 12. A vacuum is created within the cell 8 by means of pipe 13 and cock 14 leading to a vacuum main 15. The cock 14 is preferably a two-way cock which may connect the cell 8 either to the main 15 or to the atmosphere in order to release the vacuum in the cell.

The upper end of the cell 8 is closed by means of a hood 16 pressed down upon a pad of rubber or like packing material 17 and making a tight joint with a tubular member 18 fitting round the filter candle 5. Access to the spinning jet 6 is obtained through a door 20 in the chamber 3 and by unscrewing and raising the hood 16. A heating jacket 21 is provided around the candle 5 and is fed with a heating fluid passing from a main 22 through a cock 23 and inlet pipe 24 into the jacket and out by a pipe 25 and cock 26 to

an exhaust main 27. Heating pipes 28 are provided in the casing 19 and outside the cell 8. A screen 30 of wire gauze is provided in the cell 8 just below the branch pipe 9 in order to prevent the filaments 7 when first extruded from the spinning jet 6 from falling into the bottom of the cell 8 and being drawn out through the vacuum exhaust 13.

As is shown in Figure 2, the hood 16 screws on to the tubular member 18, and makes a tight joint therewith by means of a packing ring 31. The member 18 is of substantially the same diameter as the heating jacket 21, and the hood 16 when unscrewed from the member 18 can be slid upwards over the member 18 and the heating jacket 21, spring clips 32 being provided to hold it in position. A passage 33 is provided through the heating jacket 21 into the interior of the candle 5, by means of which a thermometer 34 may be inserted in order to observe the temperature of the spinning solution passing through the candle. The thermometer 34 will be removed when sliding up the hood 16 for the purpose of attending to the spinning jet. The filaments 7 are collected together by the guide 10 in the form of a thread 35 which passes round the feed roller 36 and is collected by means of a cap spinning device 37 and a bobbin 38.

The outer casing 19 protects the tube 8 from the influences of the outside atmosphere, and enables economical heating of the cell 8 by means of the heating pipes 28 to be effected. At the same time, the volume of the inner cell 8 is very small, and the vacuum therein can be created and maintained at a relatively small cost.

In Figure 3, the filter candle 5 is contained in a chamber 49 forming an enlargement at the upper end of a tubular inner cell 8. Access to the spinning jet 6 is obtained through a door 41 bedded down to form a gas-tight joint on a gasket of soft rubber 42. The spinning solution passing through the candle 5 is heated by means of a heating coil 43 connected to the supply and exhaust headers 22, 27. At the lower end of the cell 8 opposite to the branch tube 9, a branch tube 44 is provided which is covered by means of a cap 45 giving access to the lower end of the cell for cleaning and attention.

The means for creating and maintaining a vacuum within the cell 8 comprises a tube 46 leading to a nozzle 47 in the lower end of the cell 8 and a tube 48 leading to a nozzle 49 in the enlargement 49. The tubes 46, 48 are connected by means of a three-way cock 50 to a tube 51 leading to the vacuum main 15. A fluff trap 52 is interposed in the tube 51 containing baffles 53 of wire gauze or fabric, and provided with a detachable cover 54. In one position of the cock 50, the vacuum main 15 is connected to the nozzle 47 and permits of slight suction at the bottom 60 of the cell which facilitates the drawing of the filaments 7 down the cell 8. This is particularly convenient when the spinning jet 6 is being wiped, and the spinning of the filaments 7 is recommenced. When the filaments have passed down the cell 8 and out of the cell to the feed roller 36 the door 41 is closed and the cock 50 is moved to the second position which cuts off the vacuum from the nozzle 47 and connects the main 15 with the nozzle 49. The nozzle 49 exerts a powerful suction which evacuates the cell 8 and the chamber 49 so that spinning proceeds in a vacuum or substantially reduced sub-atmospheric pressure. The third position of the cock 50 cuts off the vacuum main 15 from the spinning cell altogether.

Heating of the cell 8 and the chamber 40 is effected by means of the heating pipes 28 which are provided outside the cell 8 and within the casing 49. The nozzle 37 is curved away from the lower end of the cell 8 in order to prevent filaments and filamentous particles of fluff from entering it. If any such particles should enter however, further protection is afforded to the vacuum main 45 by the fluff trap 52.

10. What we claim and desire to secure by Letters Patent is:—

1. Apparatus for the production of artificial filaments comprising a chamber of large cross-section, a spinning jet in said chamber for the extrusion of artificial filaments, a tubular cell of small cross-section leading from said chamber to receive such artificial filaments, a hood in said chamber about said jet adapted to make a gas-tight closure with said jet and with the end of said tubular cell, and to slide away from said cell to give access to said jet, a door in said chamber to give access in turn to said hood, and means for creating and maintaining a vacuum within said cell.

2. Apparatus for the production of artificial filaments comprising an outer cell, a spinning jet at one end of said outer cell for the extrusion of artificial filaments, a narrow inner cell within said outer cell adapted to receive such artificial filaments, and extending the length of said outer cell, means for creating and maintaining a vacuum in said inner cell, a hood surrounding said jet and adapted to make a gas-tight joint with the end of said inner cell and to be slid away from said inner cell to give access to said jet, and a door in said outer cell to give access to said hood and to said jet.

3. Apparatus for the production of artificial filaments, comprising an outer cell, a spinning jet at one end thereof for the extrusion of artificial filaments, heating means within said outer cell, an inner cell within and extending the length of said outer cell and adapted to receive artificial filaments extruded from said jet, means for creating and maintaining a vacuum in said inner cell, a hood surrounding said jet and adapted to make a gas-tight joint with the end of said inner cell and to be slid away from said inner cell to give access to said jet, and a door in said outer cell to give access to said hood and to said jet.

4. Apparatus for the production of artificial filaments, comprising a narrow tubular cell, a spinning jet disposed beyond one end of said cell, a hood adapted to surround said jet and to be slid back to give access to said jet, and packing means enabling said hood to form a gas-tight closure about said jet and the end of said tubular cell.

5. Apparatus for the production of artificial filaments comprising a chamber of large cross-section, a spinning jet in said chamber for the extrusion of a thread of artificial filaments, a tubular cell of small cross-section leading into said chamber and adapted to receive such artificial filaments, means for continuously exhausting the cell so as to create and maintain a vacuum therein, means in connection with said chamber for giving access to the jet therein and adapted to make a gas-tight closure about said jet and the end of said tubular cell, and an exit for the withdrawal of such artificial filaments from said tubular cell, said exit being adapted to leave only a slight clearance between it and the thread of artificial filaments passing through it.

70. 6. Apparatus for the production of artificial

filaments comprising a chamber of large cross-section, a tubular cell of small cross-section therein, a gas-tight joint between the upper end of said cell and said chamber, a spinning jet in said chamber beyond the end of said cell for the extrusion of artificial filaments into said cell, means for continuously exhausting said cell so as to create and maintain a vacuum therein, means in connection with said chamber for giving access to the jet therein and adapted to make a gas-tight closure about said jet and the end of said tubular cell, and an exit for the withdrawal of such artificial filaments from said tubular cell, said exit being adapted to leave only a slight clearance between it and the thread of artificial filaments passing through it.

7. Apparatus for the production of artificial filaments comprising an outer chamber, an inner cell enclosed therein, heating means within the said outer chamber and outside said inner cell, a spinning jet in said chamber beyond the end of said cell for the extrusion of artificial filaments into said cell, means for continuously exhausting said cell so as to create and maintain a vacuum therein, means in connection with said chamber for giving access to the jet therein and adapted to make a gas-tight closure about said jet and the end of said inner cell, and an exit for the withdrawal of such artificial filaments from said inner cell, said exit being adapted to leave only a slight clearance between it and the thread of artificial filaments passing through it.

8. Apparatus for the production of artificial filaments comprising a chamber of large cross-section, a spinning jet in said chamber for the extrusion of a thread of artificial filaments, a tubular cell of small cross-section leading into said chamber and adapted to receive such artificial filaments, means in connection with the end of said tubular cell leading into said chamber for giving a high degree of suction for continuously exhausting said cell so as to create and maintain a vacuum therein, means at the other end of said cell for giving a low degree of suction, a door in said chamber to give access to said jet, a gasket to render said door gas-tight when closed and an exit for the withdrawal of such artificial filaments from said tubular cell, said exit being adapted to leave only a slight clearance between it and the thread of artificial filaments passing through it.

9. Apparatus for the production of artificial filaments comprising an outer chamber, an inner cell enclosed therein, a spinning jet for the extrusion of artificial filaments into said inner cell, means in connection with said chamber for giving access to said spinning jet and adapted to make a gas-tight closure about said jet and the end of said inner cell, means for maintaining a suction within said inner cell while said closure means is open, means for continuously exhausting said inner cell while said closure means is closed so as to create and maintain a vacuum therein, and an exit for the withdrawal of such artificial filaments from said inner cell, said exit being adapted to leave only a slight clearance between it and the thread of artificial filaments passing through it.

10. Apparatus for the production of artificial filaments comprising a chamber of large cross-section, a spinning jet in said chamber for the extrusion of a thread of artificial filaments, a tubular cell of small cross-section leading into said chamber and adapted to receive such artificial filaments, means at the lower end of said

- cell for continuously exhausting the cell so as to create and maintain a vacuum therein, a gauze screen adapted to prevent filaments and fluff from being drawn into said exhausting means, 5 means in connection with said chamber for giving access to the jet therein and adapted to make a gas-tight closure about said jet and the end of said tubular cell, and an exit for the withdrawal of such artificial filaments from said tubular cell, 10 said exit being adapted to leave only a slight clearance between it and the thread of artificial filaments passing through it.
11. Apparatus for the production of artificial filaments comprising a chamber of large cross-section, a spinning jet in said chamber for the extrusion of a thread of artificial filaments, means 15 for heating spinning solution on its way to said spinning jet, a tubular cell of small cross-section leading into said chamber and adapted to receive such artificial filaments, means for continuously exhausting the cell so as to create and maintain a vacuum therein, means in connection with said chamber for giving access to the jet therein and adapted to make a gas-tight closure about said jet and the end of said tubular cell, and an exit for the withdrawal of such artificial filaments from said tubular cell, said exit being adapted to leave only a slight clearance between it and the thread of artificial filaments passing through it.
